MANUFACTURE OF PAPER BOARD

Application filed April 24, 1931. Serial No. 532,428.

This invention relates to the manufacture of thick, heavy board from sheets or webs of fibrous material, as paper, which product is used for electrical insulation and other purposes where a tough, dense and hard board is required.

The object of the invention is to so construct a machine, which may be of the type illustrated in United States Patent No. 1,186,881, June 13, 1916, that the fibers of the separate webs or sheets which have had a surface or surfaces coated with adhesive and are designed to be united by pressure, as by calendering or pressure cylinders, will be hydrated to such an extent that the board produced when subsequently calendered or glazed will have practically the same density throughout and be as hard and tough in the interior as on the surfaces.

In the machine illustrated several sheets or webs of strong paper, that have had one or both surfaces coated with adhesive, are fed from individual rolls about suitable bars and then upward to the nip of a pair of calendering or pressure cylinders. While the sheets are passing upward to the cylinders one or both surfaces are showered with a sufficient quantity of water to moisten the fibers to the degree required to render the adhesive adherescent and to insure the necessary hydration of the stock under the pressure of the cylinders.

The amount of water that is allowed to be absorbed is determined by the quality of the stock, the amount of size in the stock, and the density required in the finished board, and this quantity of water is regulated by adjustable gates arranged adjacent to the surfaces of the upwardly moving sheets beyond the localities where they have been showered and in such positions as will prevent the surplus water from being carried up by the sheets beyond the necessary predetermined distances. Thus treated the separate sheets unite intimately, with the fibers in the interior so moistened that further wetting of the sheets before being subsequently calendered or glazed is obviated, and the interior of the board will be uniformly hydrated.

Fig. 1 of the accompanying drawing indicates a side elevation of such features of a machine of the character mentioned as will enable this invention to be practiced. Fig. 2 is a detail view on larger scale illustrating the relations of the pressure cylinders, pipes for showering the sheets with water as they pass upward to the nip of the cylinders, and the gates which control the height that the free water can travel up with the separate sheets. Fig. 3 is a detail view of the gates and gate supporting means. Fig. 4 is a detail plan of the gate supporting means.

The machine illustrated has an upright frame 1 shown as supporting six rolls of paper 2. The invention, however, is not limited to this particular number of rolls of paper. These rolls of paper are carried by shafts 3 which are held in bearings 4 attached to the frame. The shafts are shown as having pulleys 5 provided with brakes 6, the tension of which can be regulated so that the rolls will unwind uniformly. The paper webs are drawn from the rolls around friction bars 7 that extend across the frames, and over and under tiers of friction bars 8 and 9. From the latter bars the webs are drawn together and superposed between calendering or pressure cylinders 10 which are supported by bearings 11 mounted in a frame 12. The upper cylinder bearings are provided with means, such as screws 13, for imparting the requisite pressure, which is considerable, to the webs as they pass between the cylinders. The shaft of the lower cylinder has a gear 14 with which meshes a pinion 15 on a shaft provided with a driving pulley 16. The webs after passing between and being united by the press cylinders may pass between rolls 17 and then be cut into sheets or wound into a roll upon an arbor 18 that has a gear 19 which is engaged by a pinion 20 on a shaft provided with a driving pulley 21.

The vertically arranged friction bars 9 and the cylinders 10 are so relatively positioned that the webs of paper as they pass from the bars to the cylinders travel in an inclined path. Extending horizontally across the sheets in front of and preferably adjacent to the bars 9 are pipes 22 provided with small

holes or slots from which water may be showered onto the surfaces of the webs. These pipes are connected at one end with an intake header 23 and at the other end with an outflow header 24, valves 25 being provided whereby the flow of water from any of the shower pipes may be regulated or shut off from the supply. The intake header is designed to be connected with a suitable source of water and the shower pipes are so arranged that the holes or slots will spray water upon the sheets at approximately their lowest points, or where they leave the bars 9 and start on their upward travel to the cylinders 10.

Extending horizontally between and across the webs and adjustable on the same incline as the incline of the webs are gates 26. In the embodiment illustrated the gates are in the form of rolls or spindles 27 that are carried by blocks 28 which are movably mounted on rods 29. These rods are shown as supported by the machine frames 1 and 12, on the same inclination as the sheets of paper to which the gates are respectively applied.

The gates are arranged to control the amount of water that will be absorbed by the webs, and they are adjusted according to the character of the stock, the quantity of size in the stock and the amount of hydration that is desired. The adjustment of the gates determines the time that the free water will remain in contact with the upwardly moving surfaces of the webs and consequently the amount of water that will permeate and will hydrate the stock in the interior of the finished board. When the fibers of each of the webs are thus moistened a desired percentage of moisture remains in the interior webs after they are united and pressed by the cylinders and the stock becomes so hydrated throughout that when subsequently calendered or glazed by cylinders or irons the interior of the finished board will not be spongy but will be hard and of a density substantially equal to that of the exterior surfaces.

It is well understood in the paper making art that pressure applied to the surface of paper, or like fibrous material, in the presence of water gives a hydrating effect. On thin paper this effect will extend through the sheet, but on thick paper or boards, this effect is limited to the surfaces. By the employment of the present invention a product is produced which is hydrated through the entire structure.

The invention claimed is:

1. The combination in a machine for forming board of a plurality of plies of adhesive coated fibrous material, of friction bars, pressure cylinders for pressing the plies together, said bars and cylinders being so related that the sheets travel upwardly from the former to the latter, means for showering the upwardly traveling plies between the bars and

cylinders, with water and rolls adjustably mounted between said bars and cylinders for limiting the amount of free water carried upward by the traveling sheets.

2. The combination in a machine for forming board of a plurality of plies of adhesive coated fibrous material, of friction bars, pressure cylinders for pressing the plies together, said bars and cylinders being so related that the plies travel on an incline from the former to the latter, means for showering the upwardly traveling sheets between the bars and cylinders, with water, and gates applied to the sheets intermediate the bars and cylinders for controlling the amount of free water carried upward by the traveling sheets.

3. The combination in a machine for forming board of a plurality of sheets of paper, of friction bars for the individual sheets, pressure cylinders for uniting the sheets, said bars and cylinders being so related that the sheets travel on an incline from the former to the latter, means for showering the upwardly traveling sheets between the bars and cylinders, with water and rolls bearing on the moistened sheets between the bars and cylinders.

4. The combination in a machine for forming board of a plurality of sheets of paper, of friction bars for the individual sheets, pressure cylinders for uniting the sheets, said bars and cylinders being so related that the sheets travel from the former to the latter, means for showering the traveling sheets between the bars and the cylinders with water, and gates applied to the sheets intermediate the bars and cylinders for controlling the amount of water carried by the traveling sheets.

5. The combination in a machine for forming board of a plurality of sheets of paper, of friction bars for the individual sheets, pressure cylinders for uniting the sheets, said bars and cylinders being so related that the sheets travel on an incline from the former to the latter, means for moistening the upwardly traveling sheets between the bars and the cylinders, with water, gates applied to the sheets intermediate the bars and cylinders, and means for adjusting said gates parallel with the inclined travel of the respective sheets.

6. The combination in a machine for forming board of a plurality of sheets of paper, of fixed parallel friction bars for the individual sheets, rotatable cylinders for uniting the sheets, said bars and cylinders being parallel and so related that the sheets travel on an incline from the former to the latter, pipes located between the bars and cylinders for showering the sheets of paper with water, and rolls in contact with the moistened sheets intermediate the said pipes and the cylinders.

7. The combination in a machine for forming board of a plurality of sheets of paper, of

fixed parallel friction bars for the individual sheets, rotatable cylinders for uniting the sheets, said bars and cylinders being parallel and so related that the sheets travel upwardly from the former to the latter, pipes 5 located between the bars and cylinders for moistening the sheets of paper with water, rolls in contact with the moistened sheets intermediate the said pipes and cylinders, 10 and means for adjusting said rolls parallel with the travel of the respective sheets.
